(57) **CLAIM**

The ornamental design for an integrated keyboard, as shown and described.

DESCRIPTION

FIG. 1 is a front perspective view of the integrated keyboard including a magnetic card reader. The keypads, keyboard lock and pencil holders are shown in phantom and are not part of the claimed design. The magnetic card reader is shown on the left side of the keyboard but the left side and the right side are interchangeable and the magnetic card reader can also be located on the right side of the keyboard. FIG. 2 is a plan view of the integrated keyboard including a magnetic card reader in accordance with the description of FIG. 1.

FIG. 3 is a side view of the integrated keyboard including a magnetic card reader in accordance with the description of FIG. 1

FIG. 4 is a side view of the integrated keyboard including a magnetic card reader in accordance with the description of FIG. 1

FIG. 5 is a front perspective view of the integrated keyboard including a magnetic card reader in accordance with the description of FIG. 1; and,

FIG. 6 is a rear perspective view of the integrated keyboard including a magnetic card reader in accordance with the description of FIG. 1.
